(57) **CLAIM**

The ornamental design for a shelf bracket combined with hang rod support, as shown and described.

DESCRIPTION

FIG. 1 is a perspective view of the shelf bracket portion of a shelf bracket combined with hang rod support showing our new design;

FIG. 2 is a front elevation view thereof;

FIG. 3 is a back elevation view thereof;

FIG. 4 is a right elevation view thereof;

FIG. 5 is a left elevation view thereof;

FIG. 6 is a bottom plan view thereof;

FIG. 7 is a top plan view thereof;

FIG. 8 is a perspective view of the hang rod support portion of a shelf bracket combined with hang rod support showing our new design;

FIG. 9 is a front elevation view thereof;

FIG. 10 is a back elevation view thereof;

FIG. 11 is a right elevation view thereof;

FIG. 12 is a left elevation view thereof;

FIG. 13 is a bottom plan view thereof;

FIG. 14 is a top plan view thereof;

FIG. 15 is a perspective view of the shelf bracket of FIG. 1 combined with the hang rod support of FIG. 8 showing our new design according to a first embodiment;

FIG. 16 is a front elevation view thereof;

FIG. 17 is a back elevation view thereof;

FIG. 18 is a right elevation view thereof;

FIG. 19 is a left elevation view thereof;

FIG. 20 is a bottom plan view thereof;

FIG. 21 is a top plan view thereof;

FIG. 22 is a perspective view of the shelf bracket of FIG. 1 with the hang rod support of FIG. 8 showing our new design according to a second embodiment;

FIG. 23 is a front elevation view thereof;

FIG. 24 is a back elevation view thereof;

FIG. 25 is a right elevation view thereof;

FIG. 26 is a left elevation view thereof;

(Continued)

FIG. 27 is a bottom plan view thereof; and,
 FIG. 28 is a top plan view thereof.
 The broken lines depict portions of the article and form no
 part of the claimed design.
